Primary Examiner—Raphael Barkai*(74) Attorney, Agent, or Firm*—Oliff & Berridge, PLC(57) **CLAIM**

The ornamental design for a digital audio player, as shown and described.

DESCRIPTION

FIG. 1 is a perspective view of a digital audio player showing a display in an upright position;

FIG. 2 is a front view thereof;

FIG. 3 is a rear view thereof;

FIG. 4 is a side view thereof, the opposite side view being a mirror image;

FIG. 5 is a top view thereof;

FIG. 6 is a bottom view thereof;

FIG. 7 is a perspective view of the digital audio player showing the display in a closed position;

FIG. 8 is a front view thereof;

FIG. 9 is a rear view thereof;

FIG. 10 is a side view thereof, the opposite side view being a mirror image;

FIG. 11 is a top view thereof; and,

FIG. 12 is a bottom view thereof.

The broken lines depict environmental subject matter only and form no part of the claimed design.
